UNITED STATES PATENT OFFICE.

CLARE M. RORK, OF DALLAS, TEXAS, ASSIGNOR TO J. W. SHELTON, OF DALLAS, TEXAS.

HYDROCARBON-BURNER.

946,581.

Specification of Letters Patent. Patented Jan. 18, 1910.

Application filed November 13, 1908. Serial No. 462,356.

To all whom it may concern:

Be it known that I, CLARE M. RORK, a citizen of the United States, residing at Dallas, in the county of Dallas and State of Texas, have invented certain new and useful Improvements in Hydrocarbon-Burners, of which the following is a specification.

My invention relates to new and useful improvements in hydrocarbon burners.

10 The object of the invention is to provide a burner constructed to cause a complete combustion, a more intense heat, and to obviate to a marked degree, the noise occasioned by the down draft and the combustion.

15 Finally the object of the invention is to provide a device of the character described that will be strong, durable, efficient and simple and comparatively inexpensive to construct, also one in which the several parts will not be liable to get out of working order.

With the above and other objects in view, my invention has particular relation to certain novel features of construction and operation, an example of which is described in the following specification and illustrated in the accompanying drawings, wherein:

Figure 1 is a vertical section showing my 20 burner, and Fig. 2 is a vertical section of a modified form of bowl and drip stool, Fig. 3 is an elevation of a modified form of bowl, a portion being broken away to show the interior, and Fig. 4 is a partial vertical 25 section showing another form.

In the drawings, the numeral 1 designates a cylindrical shell closed at its bottom and lower portion and having an escape opening or outlet 2 at one side of its upper 30 end. It is to be understood that while I have shown my invention in connection with an ordinary stove shell, it may be used with various kinds of stoves, furnaces and heaters.

35 The shell is closed at its upper end by a top 3 from the center of which a down draft and feed tube 4 depends. This tube terminates some distance above the bottom of the shell. A faucet or other cut-off 5 arranged on the end of a pipe 6, having connection with suitable means (not shown) for supplying a suitable oil, is disposed over the center of the tube so that the oil will drop through the same without touching the 40 inner walls thereof.

To prevent oil from being thrown into contact with the walls of the tube by the cross currents passing the lower end of the tube, the lower end of the latter is contracted to so provide an opening 7 of smaller diameter than that of the tube. This has a tendency to constantly draw the oil toward the center of the tube. If the oil is permitted to strike the inner walls of the tube it is likely to combust or explode causing a disagreeable noise and interfering with the proper operation of the burner.

Beneath the tube a combustion bowl 8 having feet 9 supporting it above the bottom of the shell, is arranged in concentric relation to the tube. The bowl may vary in shape as for instance the bowl 8 having a flat bottom and upwardly diverging side walls 10 may be used or the bowl may be rounded as shown at 11 in Fig. 2.

In the center of the bowl beneath the lower end of the tube, a drip stool 12 is arranged. The drops of oil passing through the opening 7 strike on the top of the stool and being ignited, combust. Should the oil be deflected upon striking it will be retained in the bowl by the sides thereof and ignited therein thus concentrating the generation of heat and preventing an undue spreading of the flame caused by ignition of the oil.

The stool is supported above the bottom of the bowl on legs 13 and secured in place by a bolt 14 passing through the bottom of the bowl. The stool is cut out and supported above the bottom of the bowl to afford a free circulation of the air and gases. It is understood that after the stool becomes heated, the oil upon striking the same will be converted into a gas or vapor. This is due to the proper admission of air down through the tube 4 which provides a down draft.

Any oil striking on the stool and not being vaporized, will pass down the same to the bottom of the bowl. Such oil however, will be immediately vaporized or consumed, owing to the flow of the air currents beneath the stool. In this way all of the fuel is consumed and ignited in the bowl so that no smoke or unburned gases rise out of the bowl. It is evident that an intense heat is created and the products of combustion after being spread upward into the shell from the bowl, pass through the outlet 2 to their destination. However, the intense heat created within the

shell may be utilized as desired and is sufficient for cooking and all kinds of heating and generating purposes.

The drip stool may be made in various shapes, two examples of which are given Figs. 1 and 3 and Fig. 2. A clean-out door 15 is arranged at the lower side of the shell as is shown in Fig. 1.

In Fig. 3 I have shown a form of bowl 10 which has been found to produce better results where it is desired to burn a "low" fire or use a very heavy oil. The bowl 8 is curved inwardly at its upper end 16 and receiving at its center the lower contracted 15 end 17 of the tube 4. In the portion 16 a plurality of escape openings 18 are provided. This form of bowl has a tendency to collect or direct the ends of the tongues of the flame toward the center and thus insure 20 a complete combustion.

I wish to call attention to the fact that the bowl 8 is a separate and distinct part from the bottom of the shell although it may be secured to the bottom, but it is preferable to 25 arrange the bowl so that it may be moved to facilitate cleaning or replacing. I prefer to construct the bowl with its greatest diameter considerably smaller than the inner diameter of the shell so as to provide a considerable space between the walls of the 30 bowl and the shell.

In Fig. 4 I have shown still another form comprising a shallow bowl 20 in which the drip stool is mounted. The contracted end 35 17 of the tube 4 has connection with an annular and downwardly flared spreader 21 extending beyond the bowl and supported on legs 22. This prevents the oil from

splashing out of the bowl and provides a burner of marked efficiency.

40

What I claim is:

1. In a hydrocarbon burner, the combination with an inclosed cylindrical casing, of a down draft tube depending centrally from the top of the casing, said tube having parallel side walls substantially throughout its entire length and a contracted lower extremity forming a flame shield and containing a small central aperture, a bowl centrally positioned beneath said tube, and an inverted 45 cup-shaped drip stool centrally arranged within the bowl, and a securing bolt passing centrally through the bowl and stool.

2. In a hydrocarbon burner, the combination with an inclosed cylindrical casing, of a down draft tube depending centrally from the top of the casing, said tube having parallel side walls substantially throughout its entire length and a contracted lower extremity forming a flame shield and containing a small central aperture, a bowl centrally positioned beneath said tube and materially spaced from the side walls of the casing and supported on legs to permit complete air circulation around said bowl, an 55 inverted cup-shaped drip stool supported on legs and centrally located within the bowl, and a securing bolt passing centrally through the bowl and stool.

In testimony whereof I have signed my 70 name to this specification in the presence of two subscribing witnesses.

CLARE M. RORK.
